CLAIM

The ornamental design for a shrimp tray, as shown and described.

DESCRIPTION

FIG. 1 is a perspective view from the rear left side and above a shrimp tray showing our new design;

FIG. 2 is a top plan view thereof;

FIG. 3 is a bottom plan view thereof;

FIG. 4 is a front elevation view thereof;

FIG. 5 is a rear elevation view thereof;

FIG. 6 is a left side elevation view thereof (the right side elevation being a mirror image thereof);

FIG. 7 is a section view taken along line 7—7 in FIG. 2; and,

FIG. 8 is a cross-section view taken along line 8—8 in FIG. 2.

FIG. 1

FIG. 2

FIG. 3

FIG. 4

FIG. 5

FIG. 6

FIG. 7

FIG. 8
